Patented Nov. 19, 1912.

4 SHEETS—SHEET 4.

UNITED STATES PATENT OFFICE.

WILBUR F. COLE, OF GROVER HILL, OHIO.

COMBINED CLOD CRUSHER AND PULVERIZER.

1,044,860.

Specification of Letters Patent.

Patented Nov. 19, 1912.

Application filed December 28, 1911. Serial No. 668,256.

To all whom it may concern:

Be it known that I, WILBUR F. COLE, a citizen of the United States, residing at Grover Hill, in the county of Paulding, State of Ohio, have invented certain new and useful Improvements in Combined Clod Crushers and Pulverizers; and I do hereby declare the following to be a full, clear, and exact description of the invention, such as will enable others skilled in the art to which it appertains to make and use the same.

This invention relates to an improvement in machines for crushing and pulverizing clods.

15 The principal object of the invention is to provide a machine of the character described in which its own weight is employed for crushing the clods.

Another object of the invention is to provide a machine of the class described which includes a rotary crusher, a combined drive chain and conveyer associated therewith for conveying the crushed clods rearwardly to a conveyer, and a plurality of pulverizing 25 rolls disposed in close proximity to the conveyer.

A further object of the invention is to provide a machine for the purpose described which comprises a main frame, crushing and 30 pulverizing means carried by the frame and ground wheels connected to the frame and means for raising and lowering the frame with respect to the ground wheels, whereby the crushing means may either engage the 35 clods or be disposed thereabove as the occasion may require.

A still further object of the invention is to provide a machine of the character described, which is composed of a relatively 40 few number of parts, and is therefore simple in construction and cheap to manufacture.

With these and other objects in view, the invention consists in the construction and 45 novel combination of parts herinafter fully described, illustrated in the accompanying drawings, and pointed out in the claims hereto appended; it being understood that various changes in the form, proportion, size and minor details of construction within 50 the scope of the claims, may be resorted to without departing from the spirit or sacrificing any of the advantages of the invention.

In the drawings: Figure 1 is a top plan 55 view of such a machine constructed in ac-

cordance with my invention, Fig. 2 is an elevation of the right hand side of the machine, showing the crusher in its inoperative or raised position, Fig. 3 is an elevation of the left hand side of the machine, showing the crusher in its operative or lowered position, Fig. 4 is a vertical longitudinal sectional view through the machine, the parts being shown in their operative positions, Fig. 5 is a detail view, partly in section and partly in elevation, showing the raising and lowering means for the frame, and Fig. 6 is a detail view of one of the bearings of one of the pulverizing rolls.

Like reference numerals designate corresponding parts in all the figures of the drawings.

Referring to the drawings, the invention comprises a horizontal frame consisting of spaced side and end sills 5—5 and 6—6. 75 Respectively formed in the side sills 5 intermediate the ends are alined bearings in which are journaled the ends of a transverse shaft 7. Secured upon the shaft 7 between the sills 5 is a pair of spaced wheels 8—8, 80 each of said wheels including a rim 9. Secured to the rims 9 of the wheels is a plurality of transversely disposed and radially extending crusher blades 10. Also connected to the rims 9 of the wheels and arranged intermediate the blades 10 is a plurality of clips 11, each of said clips being of U-shaped formation, and having the extremities 12 of their legs outwardly curved for a purpose hereinafter described. Ex- 85 tending forwardly of and connected to the front end sills 6, by any suitable means, is a tongue 13 to which the usual draft elements may be attached. A standard 14 is also secured at its lower end to the front sills 6, 90 and supports the usual driver's seat 15 at its upper end. Also formed on the exterior faces of the rims 9 is a plurality of sprocket teeth 16 adapted to be engaged by sprocket chains 17, said chains also being trained over 95 respective sprocket wheels 18 which are carried upon a countershaft 19, said shaft being journaled in suitable brackets 20 located on the rear portion of the frame. The ends of this shaft 19 project beyond the side sills 100 5 of the frame, and have secured thereon sprocket wheels 21 and 22 respectively. The sprocket chains 17 are connected by a plurality of transverse blades 23, which are spaced apart a distance equal to the distance 110

between an adjacent pair of clips 11. These blades 23 each have their ends projecting beyond the respective chains 17 for engagement within an alined pair of clips 11. It will be observed in this connection that as the clips 11 and the blades 23 are brought together, the curved ends 12 of said clips will permit of the blades 23 easily entering the same.

Depending from the rear ends of the side sills 5 are end walls 24 of a dirt-receiving compartment. A rear wall 25, preferably of sheet metal, connects the walls 24 and the rear sill 6. A forward wall 26 is connected to the end walls 24 of the compartment, and is disposed below the frame and in spaced relation thereto. The lower ends of the front and rear walls of said compartment are spaced apart to form a transverse opening 27 to permit of the egress of the pulverized dirt, as will be hereinafter more fully explained.

A transverse shaft 28 has its ends journaled in suitable openings formed in the end walls 24 of the dirt compartment. This shaft has its ends extending exteriorly of the walls, and provided with sprocket wheels 29 and 30 respectively. Pivottally mounted upon the shaft 28 and depending therefrom in a forwardly inclined manner, is a conveyer frame including side sills 31-31. The forward ends of the sills are pointed, as shown by the reference numeral 32, and carried by said pointed ends is a transversely disposed scraper 33, said scraper being formed of sheet steel of V-shaped construction to fit the said pointed ends. This scraper is disposed below the crusher blades and slightly in rear of the center line thereof. Journaled in suitable openings formed in the side sills 31 of the frame and directly below the upper end of the scraper 33 is a shaft 34. Fixedly secured upon the shafts 28 and 34 are upper and lower rollers 35-36 respectively. Trained around these rollers is an endless belt 37, constituting a conveyer and formed of any suitable material, said belt carrying a plurality of transversely disposed slats 38. Brackets 39 are carried by the side sills 5 of the frame, and extending through each bracket is the threaded outer end 40 of a rod 41 which has its other end pivotally connected to the side sills 31 of the conveyer, as indicated by the reference numeral 42. Associated with the threaded end 40 of each rod is an adjusting nut 43, by means of which the conveyer frame may be adjusted to or from the blades 23 of the sprocket chains 17.

Disposed within the dirt-receiving compartment and below the upper end of the conveyer 37, is a pair of crushing rolls 44 and 45 respectively. Each of these rolls is provided with a plurality of teeth 46, which

are respectively disposed in staggered relation, so as to clearly pass one another when said rolls are rotated. These rolls are transversely disposed, and the roll 44 is formed with suitable trunnions 47 and 48 respectively, which are journaled in suitable openings in the side walls 24 of said dirt-compartment. The trunnion 48 projects beyond said wall, and has fixedly secured thereon a sprocket wheel 49. The roll 45 is also formed with suitable trunnions 50, and these trunnions project through and beyond elongated bearings 51 formed in the side walls 24 of said compartment. A cap 52 is secured to the exterior face of each wall 24 and around the respective trunnion 50. A sleeve 52^a is mounted upon the projecting end of each trunnion and disposed between the sleeve and the wall of the cap is a coil spring 53. These springs 53 tend to urge the roll 45 toward the roll 44.

Disposed within the dirt-receiving compartment and arranged below the rolls 44 and 45, is a smooth roll 54. This roll is likewise transversely disposed, and is provided at its ends with trunnions 55, which are respectively journaled in suitable openings formed in the side walls 24. One of the trunnions 55 projects beyond the side wall 24, and has fixedly secured thereon a sprocket wheel 56. It will be observed in this connection that the sprocket wheels 30, 49 and 56 are all disposed on the same side of the machine, and are arranged in alignment with the sprocket wheel 22. In order to drive the rolls, there is provided a sprocket chain 57 which is trained over the sprocket wheels 22, 30, 49 and 56, the chain being so trained as to rotate the rolls 44 and 54 toward each other so as to force the dirt downwardly through the egress opening 27.

In order to actuate the conveyer belt 37, there is provided a sprocket chain 58 which is trained over the sprocket wheels 21 and 22 respectively.

Disposed between the roll 55 and the forward wall 26 of the casing of the compartment, is a curved plate 59, the upper end thereof being connected to the wall 26 by a hinge 60 of any suitable construction. In order to hold the plate 59 at any predetermined point from the roll 54, there is provided a plurality of set-screws 61 which project through the wall 26 of the compartment.

In order to support the rear end of the machine, I have provided a caster wheel 62 which is journaled between the forks of a suitable standard 63 that is connected to a bracket 64 fixedly secured to the wall 26 of the compartment.

In practice, when the machine is drawn along over plowed ground, the weight of the machine will cause the blades 10 of the

wheels 8 and also cause the blades 23, which are carried by the clips 11, to be forced into the ground, and thereby crush the clods with which they come in contact. As the 5 machine moves along the sprocket chain 17 is of course rotated, and through the medium of the sprocket wheel 21 the conveyer belt 37 is actuated. At the same time the sprocket chain 57 causes the rolls 44 and 54 10 to be rotated in reversed directions. It will thus be observed that the blades 10 and 23 coöperate to crush the clods, and the blades 23 thereupon move over the point 33 of the scraper and over the conveyer belt 37, carrying the crushed dirt to said conveyer. This conveyer then deposits the dirt into the dirt-receiving compartment and between the crusher rolls 44 and 45. These rolls coöperate to further crush the dirt and after 15 passing therethrough the dirt drops between the smooth roll 54 and the curved plate 59. As the dirt passes between the last mentioned roll and the plate 59, it is pulverized and then the dirt passes downwardly and out through the egress opening 25 27 to the land.

In order to easily transport the machine from place to place, there is attached to the side sills 5 of the frame, brackets 65, each 30 bracket including spaced vertical guide flanges 66. Movably mounted between the flanges is an arm 67, which is formed with a plurality of rack teeth 68. The lower end of the arm 67 is formed with a stub axle 69, 35 and mounted upon said axle is a ground wheel 70. Suitable brackets 71 are carried by the side sill 5 of the frame, and journaled in said brackets is a shaft 72 having at one end a pinion 73, which meshes with 40 the rack 68. Carried by the other end of the shaft 72 is a bevel pinion 74 which meshes with a similar pinion 75, which is carried by one end of a vertical shaft 76. The last mentioned shaft has its lower end 45 suitably journaled in a bearing 77, and is held in its vertical position by means of a brace 78. Fixedly secured to the upper end of the shaft 76 is an operating handle 79. By means of this construction it will be 50 observed that upon rotation of the handle 79 the shafts 76 and 72 will be actuated, and through the medium of the pinion 73, which meshes with the rack 68, the corresponding ground wheel 70 can be raised or 55 lowered as desired. In order to securely hold the ground wheels in any adjusted position, I have provided a pawl 80 which is pivotally mounted upon the arm 65 and adapted to engage the rack 68.

60 From the foregoing, it will be observed that when the machine is being transported from place to place, the ground wheels 70 are lowered to the position shown in Fig. 2 of the drawings. When, however, it is 65 intended to operate the machine, the ground

wheels 70 are raised and held in such position, as clearly shown by reference to Figs. 3 and 4 of the drawings.

An arcuate shield 81 has one end connected to the frame, and is disposed between 70 the seat 15 and the crushing means to prevent any accidental contact with the said means.

What is claimed is:—

1. A machine of the class described including a pair of wheels, clips projecting from the peripheries of said wheels, transverse blades rigidly secured to the peripheries of the wheels and disposed intermediate the clips, a shaft, sprockets carried by 75 the shaft, and disposed in alinement with the wheels, sprocket chains trained over the respective wheels and sprockets, transverse blades carried by the chains and spaced apart for engagement with the clips of the 80 wheels, a conveyer disposed below the chains, a scraper carried by the conveyer, pulverizing means disposed adjacent the end of the conveyer opposite the scraper, and actuating means for the pulverizing means 85 90 and the conveyer connected to said shaft.

2. A machine of the class described including a pair of wheels, clips projecting from the peripheries of said wheels, transverse blades rigidly secured to the peripheries of the wheels and disposed intermediate the clips, a shaft, sprockets carried by 95 the shaft and disposed in alinement with the wheels, sprocket chains trained over the respective wheels and sprockets, transverse 100 blades carried by the chains and spaced apart for engagement with the clips of the wheels, a conveyer frame pivotally mounted at one end below the chains, a conveyer mounted upon said frame, a scraper carried 105 by the frame and disposed opposite the pivot thereof, and means for adjusting the conveyer with respect to the chains.

3. A machine of the class described including a main frame, a pair of wheels rotatably supported by said frame, clips projecting from the peripheries of said wheels, transverse blades rigidly secured to the peripheries of the wheels and disposed intermediate the clips, a shaft, sprockets carried 110 by the shaft and disposed in alinement with the wheels, sprocket chains trained over the respective wheels and sprockets, transverse blades carried by the chains and spaced apart for engagement with the clips of the 115 wheels, a conveyer disposed below the chains, a scraper carried by the conveyer, ground wheels connected to the frame for respective vertical movement, and means for raising and lowering the frame with 120 respect to said ground wheels.

4. A machine of the class described including a main frame, a pair of wheels rotatably supported by said frame, clips projecting from the peripheries of said wheels, 125 130

4

transverse blades rigidly secured to the peripheries of the wheels and disposed intermediate the clips, a shaft, sprockets carried by the shaft and disposed in alignment with the wheels, sprocket chains trained over the respective wheels and sprockets, transverse blades carried by the chains and spaced apart for engagement with the clips of the wheels, a conveyer disposed below the chains, a scraper carried by the conveyer, pulverizing means disposed adjacent the end of the conveyer opposite the scraper, actuating means for the pulverizing means and the conveyer connected to said shaft, ground wheels connected to the frame for respective vertical movement, and means for raising and lowering the frame with respect to said ground wheels.

5. A machine of the class described including a main frame, a pair of wheels rotatably supported by said frame, clips projecting from the peripheries of said wheels, transverse blades rigidly secured to the peripheries of the wheels and disposed intermediate the clips, a shaft, sprockets carried

by the shaft and disposed in alignment with the wheels, sprocket chains trained over the respective wheels and sprockets, transverse blades carried by the chains and spaced apart for engagement with the clips of the 30 wheels, a dirt-receiving compartment including end walls depending from the frame in spaced relation to said wheels, a conveyer frame disposed below the sprocket chains and pivotally connected to the walls 35 of said compartment, a scraper carried by the lower end of the conveyer frame, a conveyer belt carried by the frame, means connecting the conveyer frame and the main frame for adjusting the former with respect to the sprocket chains, and pulverizing means disposed in said dirt receiving compartment.

In testimony whereof, I affix my signature, in presence of two witnesses.

WILBUR F. COLE.
